UNITED STATES PATENT OFFICE.

JULIUS H. HILDEBRANDT, OF CLEVELAND, OHIO.

OIL BURNER.

Application filed May 12, 1924. Serial No. 712,510.

To all whom it may concern:

Be it known that I, JULIUS H. HILDEBRANDT, a citizen of the United States, residing at Cleveland, in the county of Cuyahoga and State of Ohio, have invented a certain new and useful Improvement in an Oil Burner, of which the following is a full, clear, and exact description, reference being had to the accompanying drawings.

10 This invention relates to liquid fuel burners, particularly those wherein the fuel is fed by gravity while a forced draft supplies air for supporting combustion.

One of the problems presented by the operation of an oil burner is the fact that the oil contains a gummy substance which has a tendency to stick to metal and thereby to clog the fuel passageways. Another problem is to supply the fuel in such manner as 20 to prevent volatilization thereof, before it reaches the combustion chamber and thereby to prevent preignition with the consequent accumulation of carbon in the form of soot in any of the passageways or distributing chambers.

My invention contemplates the provision of an oil burner having the fuel supply so arranged that the oil is maintained as cool as possible before being ejected into the combustion chamber. In this connection my invention is directed towards the provision of a fuel supply apparatus which is so arranged that the various parts are not affected by the expansion of one part at a greater 30 rate than another part as a result of a difference in the degree of temperature to which the parts are subjected.

A further object of my invention is the provision of an oil burner which may be readily assembled in furnaces having comparatively small combustion space, and which when once installed, may be readily dismantled for cleansing purposes through the usual fire door opening. In addition I 40 provide a burner which is economical in consumption of fuel and which requires comparatively little machine work to effect proper coordination between the component parts.

Still another object of my invention is the arrangement of means for preventing the flow of excess oil into the ash pit, in the event the flame is extinguished, while the fuel is turned on, and to so construct such means that the intense heat in the combustion 55 chamber cannot crack or break any of the parts which would interfere with the normal functioning of this automatic shut-off means.

The preferred means for carrying out my invention is illustrated in the accompanying drawings and is hereinafter set forth in detail in the following description. The essential features are summarized in the 60 claims.

In the drawings Fig. 1 is a vertical section through a portion of a furnace showing my invention installed therein; Figs. 2 and 3 are sections taken on the corresponding numbered lines in Fig. 1; Fig. 4 is a section 70 taken on a plane indicated by the line 4-4 in Fig. 6; Fig. 5 is a longitudinal section taken on an enlarged scale through the lower portion of the fuel supply conduit and Fig. 6 is a section taken on the line 6-6 in 75 Fig. 4.

My invention is illustrated as within a furnace, the walls of which are indicated at 10, and the base of which is illustrated at 11. A grate 12 is disposed across the top of the base, and represents any suitable or convenient form of grate. An opening 13 in the base may comprise the usual opening for the ash pit door, while an opening 14 in the furnace walls indicates an opening for a 80 fire-box door. The burner is adapted to be positioned upon the grate and is arranged to be assembled through the fire box door opening. The conduits through which the fuel and air are conducted are preferably 85 arranged to be led through the ash pit door opening.

The burner illustrated comprises a base 15, which rests upon the grate and supports the fuel distributing mechanism. The base 90 also has a flange 17 through which spaced openings 18 extend. The top of the flange 95 supports a member 19 which forms part

of an air conduit. The preferred manner of supporting the conduit is as shown in Fig. 6 to employ shoulders 20, which are spaced in such manner as to permit the passage thereof through the openings 18 for enabling the conduit to be positioned from the bottom of the grate.

Disposed above the baffle 16, I have shown a conical baffle 21, the interior of which is 10 hollow, as at 22, for providing a continuation of the air conduit 19. The exterior part of the baffle 21 is curved downwardly and outwardly adjacent the bottom thereof as at 23, to provide a trough or receptacle 15 within which fuel may collect. The members 19 and 21 therefore provide an air conduit which communicates with an air supply pipe 24 and which provides a housing for the fuel supply pipe. A blower (not 20 shown) is attached to the supply pipe outside the furnace, wherefore the air functions to maintain the fuel, at a low temperature before it is distributed over the baffle 21.

25 The oil may be arranged to enter the burner from a supply pipe 25 which extends through a gas conduit 26 and communicates with the passageway 27 in a distributor 28. From the distributor the liquid fuel flows 30 downwardly through passageways shown as pipes 29, so as to distribute the fuel uniformly over the surface of the baffle 21. This distributor is supported preferably by a threaded connection 30, one end of which 35 extends into a boss 31 which forms part of a gas distributor 32. This distributor in turn may be threaded to receive the gas conduit 26, which as shown in Fig. 1 is maintained in proper position by means of a nut 33. 40 Thus the gas distributor 32 and oil distributor 28 are maintained out of contact with the baffle 21 wherefore the baffle may expand at a greater rate than the comparatively cool surfaces in the region of the distributor.

45 The air for supporting combustion may be led into the burner through the supply pipe 24, conduits 19 and 22, from whence it is ejected into the furnace. The means 50 for directing the flow of air preferably embodies a hood 40 shown as an inverted cup-shaped member. The hood in the preferred form is supported by a spider 41 which may comprise three arms extending downwardly 55 and outwardly from a central hub 42, and resting upon the distributor 28. A securing member 43 may then be used for clamping the hood to the spider. The fuel distributor, as shown in Fig. 1, is sufficiently 60 small in diameter to permit the passage of air over and around the fuel which is flowing down the sides of the distributor. This functions to maintain the oil at a low temperature, while the moving current of air

tends to prevent the accumulation of 65 gummy deposits from the oil.

To permit automatic operation of a burner made in accordance with my invention, I have shown means for maintaining a pilot light in operation, notwithstanding 70 the rush of air due to the forced draft. This pilot is operated by gas which may be lead through the conduit 26, the lower end of which terminates in a member 45. A pipe 46 may communicate with the chamber in 75 the member 45, while a stuffing box 47 prevents the escape of gas along the conduit 25. The gas thus flows upwardly and enters the distributor 32 which in the preferred form comprises hollow arms which extend outwardly and downwardly intermediate the oil distributing pipes 29. Thus the flame from the pilot light is directed downwardly on the conical surface of the baffle 21, wherefore such baffle can be maintained sufficiently hot to insure ignition when the oil is turned on.

To provide an automatic shut-off in the event the oil flame is extinguished while the fuel is turned on, I provide a groove 50 in the upper surface of the base 15 from which a conduit 51 extends into an overflow receptacle 52. This receptacle communicates with an automatic shut-off valve (not shown). To permit excess fuel to enter the 90 groove or receptacle 50 I have shown the flange 17 on the base as extending above a flange 54 on the baffle 15. Moreover, I have shown the outer edge of the baffle 16 as being higher than the top surface of the flange 100 54 wherefore fuel will overflow into the receptacle 50 rather than over the outer edge of the baffle. To permit free passage of fuel through the receptacle, the diameter of the flange 54 is greater than that of the flange 105 17 as shown particularly in Fig. 1. The excess fuel enters the dish-shaped baffle 16 by flowing over the edges of the receptacle 23 and then underneath the conical baffle.

An important advantage of utilizing the 110 base as a collector for excess fuel is that refractory material such as fire brick may be placed over the dish-shaped baffle, wherefore the base is at no time subjected to a high degree of heat sufficient to crack or 115 warp the upper surface thereof and thereby to permit the escape of fuel into the ashpit. Moreover, the use of the base as a collector is advantageous since the function thereof is not destroyed, even though the dish-shaped baffle is cracked or broken.

To insure circulation of air in the upper region of the hood, I have shown a plurality of spaced openings 55 which extend upwardly through the distributor 28 and thereby permit some of the air flowing out of the conduit 22 to pass through the distributor, and then downwardly between the

distributor and the hood. Thus the moving current of air across the face of the distributor tends to maintain the sloping passageways on the distributor in operative condition by preventing the accumulation of 5 gummy substance thereon.

My invention is well adapted for installation within the fire box of a furnace through the usual fire-box opening. For 10 example, the base 15 is positioned on the grate and the baffle 16 is placed over the base. Then the conduit 19 is moved upwardly through the grate in such manner that the lugs 20 pass through the openings 15 18 in the flange 17. When the lugs are at the top of the flange, the conduit is rotated with reference to the base so that the lugs occupy the position shown in Figs. 4 and 6. Thereupon, the concentric conduits 25 and 20 26 may be passed through the fire door opening and then through the conduit 19 until the nut 33 engages the pad 56 shown in Fig. 1. Then the distributor 28 which has 25 previously been provided with pipes 29 and distributor 32 is placed over the upper end of the fuel and gas supply conduit, whereupon these pipes may be turned to effect connection with the gas distributor. Access to the pipe for turning purposes may 30 be had through the ash pit door opening. After this adjustment is effected, then the spider 41 is placed over the oil distributor whereupon the hood is brought into engagement with the latter and attached thereto. 35 Connections for the air, gas and oil are then made in the usual way.

In view of the foregoing description it will be evident that my invention provides means for supplying fuel to the burner in 40 such manner that the fuel is maintained at low temperature until it is ejected into the combustion zone. This prevents volatilization of the oil and subsequent deposits of carbon within the burner before the oil is ignited. Moreover, the parts which are subjected to the intensive heat of the flame, are 45 remote from the receptacle which collects the overflow and conducts it to a shut-off mechanism. In this connection my invention embodies a burner, the parts of which 50 may be readily assembled with comparatively little machine work being required to insure proper coordination.

I claim:

55 1. In an oil burner, the combination with an air supply conduit of a fuel supply conduit disposed therein, a fuel distributor associated with said fuel supply conduit, a hood surrounding said distributor and terminating below the bottom thereof, said distributor having an upwardly facing surface and having openings therethrough whereby some of the air flowing through the conduit may pass upwardly through the distributor and said hood functioning to

deflect some of the air downwardly and over the face of the distributor, a baffle beneath the hood for directing a mixture of fuel and air outwardly, and an overflow conduit leading from the burner beneath the baffle. 70

2. In an oil burner, the combination with an air supply pipe of a liquid fuel supply conduit and a gas supply conduit disposed within the pipe, a distributor associated with each conduit, each of said distributors 75 having spaced passageways leading downwardly, a member surrounding said distributors and being in spaced relation thereto, whereby air may pass upwardly through the pipe and then downwardly across the 80 face of one of the distributors and whereby part of the air may flow through some of the passageways and part may flow between the distributors and said members.

3. In an oil burner, the combination with 85 a base having a flange adjacent the midportion thereof, an air conduit having a shoulder engaging the flange, a dish-shaped baffle supported on the base in such manner that the inner top edge of the baffle is disposed 90 beneath the top of the flange, a conical baffle disposed above the first mentioned baffle, a fuel conduit within the air pipe, a distributor connected to the conduit above the upper baffle, means for deflecting air downwardly over the distributor and then over 95 said baffle and an overflow conduit leading from the base.

4. In an oil burner, the combination with 100 an upwardly extending air pipe, of a gas conduit and a liquid fuel conduit, extending through the pipe, one of said conduits surrounding the other, a distributor communicating with the fuel conduit, a plurality of passageways extending downwardly from 105 the distributor, a member extending laterally from the gas conduit and leading downwardly in the same general direction as said passageways, and means for deflecting a mixture of fuel and air in the same general 110 direction as the flow of gas.

5. In an oil burner, the combination with 115 an air pipe, of a gas conduit disposed within the pipe and supported adjacent the bottom thereof, a gas distributor communicating with the pipe and comprising spaced arms extending laterally and downwardly whereby gas is ejected downwardly over the sides of the air pipe, a fuel supply pipe extending through the gas conduit, a fuel distributor communicating with the fuel supply pipe over the air pipe, spaced passageways leading downwardly from the distributor, and means for deflecting air downwardly over said distributor. 120

6. In an oil burner, the combination with 125 a base, of a baffle disposed thereabove, an air supply conduit extending through the base and baffle, a gas conduit extending through the air pipe, a liquid fuel supply conduit ex-

tending through the gas conduit, a distributor communicating with the gas conduit above the baffle and out of contact therewith, a second distributor connected with the fuel 5 conduit and carried by the first mentioned distributor, a hood surrounding both distributors and serving to deflect the combustible mixtures downwardly over said baffle,

and means for so connecting the air pipe and one of the conduits that the weight of 10 the distributor and deflecting means is carried by the air pipe independently of said baffle.

In testimony whereof, I hereunto affix my signature.

JULIUS H. HILDEBRANDT.
